Primary Examiner — Leanne Was-Englehart
Assistant Examiner — Devin Kelly

(57) **CLAIM**

The ornamental design for a relay assembly, as shown and described.

DESCRIPTION

FIG. 1 is a perspective view of a relay assembly, showing my new design;

FIG. 2 is a perspective view from another angle of view thereof;

FIG. 3 is a perspective view from the other angle of view thereof;

FIG. 4 is a front elevational thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view of one of the electronic components of FIG. 1;

FIG. 11 is a perspective view from another angle of FIG. 10;

FIG. 12 is a perspective view of another electronic component of FIG. 1;

FIG. 13 is a perspective view from another angle of FIG. 12;

FIG. 14 is a perspective view of the other electronic component of FIG. 1; and,

FIG. 15 is a perspective view from another angle of FIG. 14. The broken lines depict portions of the relay assembly that form no part of the claimed design.

1 Claim, 13 Drawing Sheets
